US00D577333S

(12) **United States Design Patent**
Daniel et al.

(10) **Patent No.:** US D577,333 S
(45) **Date of Patent:** ** Sep. 23, 2008

(54) **RECHARGEABLE BATTERY ASSEMBLY**

(75) Inventors: **Simon Richard Daniel**, Surrey (GB);
Christopher Verity Wright, Stroud (GB)

(73) Assignee: **Moxia Energy Holdings Limited**, London (GB)

(**) Term: **14 Years**

(21) Appl. No.: **29/247,130**

(22) Filed: **Jun. 1, 2006**

(51) **LOC (8) Cl.** 13-02

(52) **U.S. Cl.** D13/103

(58) **Field of Classification Search** D13/102-106,
D13/110, 118-119, 184; 429/96-100, 163,
429/176

See application file for complete search history.

(57) **CLAIM**

The ornamental design for a rechargeable battery assembly, as shown and described.

DESCRIPTION

FIG. 1 is a perspective view from one end and the side of a rechargeable battery assembly with the cap on showing our new design. The broken line showing is included for the purpose of illustrating environmental features and forms no part of the claimed design;

FIG. 2 is a perspective view from the other end and the side of a rechargeable battery assembly shown in FIG. 1 with the cap on. The broken line showing is included for the purpose of illustrating environmental features and forms no part of the claimed design;

FIG. 3 is a perspective view from the other end and the side of a rechargeable battery assembly shown in FIG. 1 with the cap partially off. The broken line showing is included for the purpose of illustrating environmental features and forms no part of the claimed design; and,

FIG. 4 is a side elevation of rechargeable battery assembly shown in FIG. 1 with the cap off. The broken line showing is included for the purpose of illustrating environmental features and forms no part of the claimed design.
